WINDOW AND VENTILATOR ACTUATOR
AND LOCKHamilton S. Carlton and Herbert E. Morrow,
Fresno, Calif.

Application July 18, 1951, Serial No. 237,466

4 Claims. (CL 268—119)

1

This invention relates to window and ventilator operating and locking or latching devices, and in particular an arm actuated by a hand crank through latching elements whereby with the crank pressed into a small casing and turned the position of a window, such as a casement window or ventilator is adjusted to a partly open position and which, when the crank is released, will not operate to open the window to a different position until the window has been closed.

The purpose of this invention is to provide a window and ventilator operating device with which a sash is partly opened and which locks the window in the partly opened position preventing further opening thereof until the window has been closed whereby it is impossible for an intruder to open the window sufficiently to permit passage therethrough and also where it is impossible for the window to be accidentally opened by a child.

Various types of operating devices have been provided for casement windows and ventilators but in the conventional type of crank operated device a hand may be placed through the partly opened window and the device may be operated to open the window sufficiently to permit entrance of an intruder or the like. With this thought in mind this invention contemplates a latch mechanism incorporated in a window operating device whereby a window is set by a hand crank to a partly opened position and after the crank is released it is impossible to open the window further until the latching means has been released by moving the window to a closed position.

The object of this invention is, therefore, to provide means for incorporating latching instrumentalities in a hand crank operating device for pivotally mounted windows, ventilators, and the like whereby it is possible to lock the windows or ventilators in partly open positions.

Another object of the invention is to provide an automatically locking window operating device that may be installed on windows now in use without changing the design or construction thereof.

A further object of the invention is to provide latching means in a window and ventilator operating device in which the operating device is of a simple and economical construction.

With these and other objects and advantages in view the invention embodies a casing adapted to be positioned on a window sill with an operating arm journaled therein and extended therefrom and having means on the outer end for slidably connecting the arm to the sash of a window or ventilator, a transversely positioned

2

shaft also journaled in the casing and having means thereon for operating the arm, a hand crank slidably mounted on the outer end of the shaft, a latch for preventing rotation of the shaft in one direction and a cam for actuating the latch to the position of releasing the shaft.

Other features and advantages of the invention will appear from the following description taken in connection with the drawings wherein:

10 Figure 1 is a sectional plan through a window of the casement type showing the operating device installed thereon and showing the window in the closed position.

15 Figure 2 is a sectional plan through the casing of the operating device showing the parts with the sash in the position shown in Figure 1.

Figure 3 is a cross section through the lower part of the sash and window frame and showing the operating device mounted on the frame with 20 part of the said operating device broken away and shown in section.

Figure 4 is a cross section through the casing taken on line 4—4 of Figure 2 showing the hand crank mounting and illustrating the parts with 25 the crank extended.

Figure 5 is a similar view showing the crank pressed inwardly in which position the ratchet teeth ride on the under surface of the latch member or bar.

30 Figure 6 is a longitudinal section through the operating casing taken on line 6—6 of Figure 2.

Figure 7 is a sectional plan similar to that shown in Figure 1 showing the sash in a partly open position.

35 Figure 8 is a sectional plan similar to that shown in Figure 2 showing the positions of the parts with the sash extended as illustrated in Figure 7.

Figure 9 is a section through the operating casing taken on line 9—9 of Figure 8 showing the latch bar dropped downwardly and with a latch thereon positioned between the teeth of the ratchet.

40 Figure 10 is a detail similar to that shown in Figures 4 and 5 with the shaft and hand crank shown in elevation illustrating the latch bar in the position of holding the hand crank outwardly.

Figure 11 is a detail showing the ratchet wheel and illustrating the wheel on a square shaft.

45 Figure 12 is a fragmentary detail illustrating part of the latch bar.

Figure 13 is a detail illustrating a section of the hub of a window sash operating arm and showing a cam in the upper face of the hub.

50 Figure 14 is a detail similar to that shown in

Figure 11 illustrating the ratchet wheel mounted on the shaft through splines.

Figure 15 is a sectional plan through a portion of the operating casing and illustrating a modification wherein teeth are provided in the end of a sleeve positioned on the hand crank whereby the ratchet wheel is eliminated.

Figure 16 is a cross section through the casing, similar to Figure 4, illustrating the position of the tubular shaft with the teeth formed in the end thereof.

Figure 17 is a section illustrating a latch bar of the type used with the operating device illustrated in Figure 15.

Referring now to the drawings wherein like reference characters denote corresponding parts the improved window operating device of this invention includes a box-like casing 10, a transversely disposed shaft 11 journaled in the casing and having a worm 12 thereon, a hand crank 13 slidably mounted on the shaft, a latch bar 14 pivotally mounted in the casing and having a tooth 15 thereon, a ratchet wheel 16 positioned over the shaft 11, an arm 17 pivotally mounted by a vertically disposed shaft 18 in the casing 10 and a guide 19 adapted to be positioned on a sash 20 and adapted to be connected to the arm 17 by a pin 21 having a roller 22 thereon.

The small housing or casing 10 is provided with end walls 23 and 24, a lower panel 25, an upper panel 26 and a cover plate 27. The cover plate 27 is held in position by screws 28 that are threaded in the lugs 29 in the corners of the casing.

The shaft 11, which is formed as illustrated in Figures 4 and 5, is journaled, at the point 30 in an opening 31 in the base of the casing and the shaft is held in position by a set collar 32 that is secured on the outer end of the section 30 by a set screw 33. The opposite end of the shaft 11 is provided with a square section 34 and a spring 35 is provided in a socket 36 in the end of the said square section.

The shaft is also provided with a tubular section having a square end 37 that is longitudinally slidable on the section 34 and the end 37 extends from a hub 38 that extends through the cover plate 27 of the casing and that is provided with a socket 39 in which a pin 40 with the hand crank 13 thereon is secured by a set screw 41.

The ratchet wheel 16 is positioned on the inner end of the end 37 of the tubular shaft and with the parts in the position shown in Figure 5 wherein the crank 13 is held inwardly the ratchet wheel rides against the under surface of the latch bars 14, as illustrated in Figure 6. With the parts in this position the shaft 11 is rotated by the crank 13 to adjust the position of the arm 17, the worm 12 meshing with the worm gear teeth 42 in the hub 43 on the end of the arm 17, and when the crank is released the spring 35 urges the tubular shaft section outwardly with the ratchet wheel 16 passing beyond the latch bar and with the tooth 15 dropping into engagement with one of the teeth of the ratchet wheel 16.

The latch bar 14 is pivotally mounted in ears 44 and 45 by a pin 46 that extends through an opening 47 in the latch bar and the opposite end of the bar is provided with an arcuate surface 48 that rides upwardly over the corresponding surface 49 of a cam 50 that is positioned on the upper surface of the hub 43 of the arm 17 and as the arm 17 moves backward to the position shown in Figures 1 and 2 the cam 50 engages

the arcuate surface on the end of the latch bar 14, moving the latch bar upwardly to the position shown in Figure 6 whereby the tubular end of the shaft is free to be moved inwardly by the crank 13. With the latch bar dropped downwardly to the position shown in Figure 9 the teeth of the ratchet wheel engage the side of the latch bar and prevent the crank 13 and outer section of the shaft being moved inwardly.

10 The arm 17 is provided with a hub 51 and the hub is positioned between the upper and lower panels of the casing by spacing sleeves 52 and 53.

With the parts as disclosed and described, and starting with the window closed as illustrated in Figure 1 wherein the cam 50 holds the latch bar 14 upwardly as shown in Figure 6, the crank 13 is pressed inwardly with the ratchet wheel 16 passing under the latch bar 14 whereby the crank is rotated in a counter-clockwise direction with the worm 12 turning the hub 43 and arm 17 outwardly to the position shown in Figure 7. In this movement the cam 50 moves beyond the end of the latch bar 14 and the latch bar is retained in the upward position by the teeth of the ratchet wheel 16 which slide against the under surface of the latch bar.

With the sash 20 of the window in the position shown in Figure 7 the hand crank 13 is released whereby the spring 35 snaps the hand crank outwardly drawing the ratchet wheel 16 away from the latch bar 14 so that the latch bar drops downwardly to the position shown in Figure 9 with the tooth 15 dropping inward between the teeth of the ratchet wheel. By this means the crank 13 is held outwardly. In this position the crank can be rotated in a clockwise direction only whereby the arm 17 is actuated to close the window. The tooth 15 prevents rotation of the ratchet wheel in the opposite direction to open the window so that the window can only be operated to the closing position, however, when the sash reaches the closed position the cam 50 again elevates the latch bar 14 whereby the window is again adapted to be opened. The window, therefore, is only adapted to be operated from the inside when it is adjusted to a partly open position and it is only adapted to be closed by the latch whereby opening travel thereof is prevented.

15 In the design illustrated in Figures 15, 16 and 17 wherein teeth 54 are provided in the end of a hub 55 similar to the end 37 of the tubular shaft section in which the crank 13 is positioned and these teeth are positioned to receive a tooth 56 from a latch bar 57 that is pivotally mounted in the casing 58 by a pin 59 and as the window is closed the latch bar 57 is moved upwardly by a cam 60 on a hub 61, similar to the hub 43.

With the latch bar 57 held upwardly the shaft 62, which is journaled in the casing 58, is free to rotate in a counterclockwise direction with the worm 63 meshing with the worm gear teeth 64 of the hub 61 for operating the hub to open the window and when the window is adjusted to the position desired the crank on the end of the shaft 65 is released whereby the hub 55 moves outwardly to permit the latch bar 57 to drop downwardly to the position shown in Figure 17 wherein the tooth 56 engages the teeth 54 to prevent rotation of the hub in the counterclockwise direction. The latch bar 57 is urged in the position shown in Figure 15 by a spring 65 which is secured in the casing by a screw 67. The shaft 62 is journaled in the casing 58 with a pin and set collar similar to corresponding parts as in-

dicated by the numerals 31 and 32 in the design shown in Figure 5 and the hub 61 of an arm similar to the arm 17 is journaled in the casing on a shaft 68.

The parts 55 and 65, referring to the hub and shaft are also similar to corresponding parts shown in Figure 5 and the shaft 65 in which a crank 69 similar to the crank 13 is mounted is secured by a screw 70 and a pin 71. The hub and shaft are also resiliently urged outwardly by a spring 72 which is positioned in the hub 55 in the inner end of which the teeth 54 are provided as shown in Figure 16.

With the parts arranged in this manner the crank 69 is moved inwardly, similar to the section of the crank 13 and by this means the arm, similar to the arm 17 is actuated to adjust the window sash in a partly opened position, as illustrated in Figure 7. In this movement the latch bar 57 is held upwardly by the cam 60 and upon release of the crank 69 the latch bar 57 drops downwardly with the tooth 56 engaging the teeth 54 allowing the crank to be rotated to close the window and preventing rotation thereof for opening the window.

In the design illustrated in Figure 14 a ratchet wheel 13, similar to the wheel 16 is slidably mounted on an end 74 of a shaft, similar to the shaft 11 with splines 75 whereby the outer tubular section of the shaft is free to slide longitudinally to permit inward movement of the crank 13 and also to permit outward movement thereof by a spring 76 that is positioned within the member 74.

It will be understood that other modifications may be made in the design and arrangement of the parts without departing from the spirit of the invention.

What is claimed is:

1. In a window sash operator, the combination which comprises a window frame, a sash pivotally mounted in the window frame, a casing positioned on the window frame, an arm pivotally mounted in the casing and extending therefrom, means operatively connecting the extended end of the arm to the sash, said arm having a hub with worm gear teeth in the peripheral surface on the end thereof positioned in the casing, a worm gear positioned in the casing and meshing with the teeth of the hub of the arm, a shaft extended through the casing for mounting the worm gear, a tubular section slidably mounted on one end of the shaft, a hand crank carried by the outer end of the tubular section of the shaft, a ratchet wheel mounted on the tubular section of the shaft, a latch bar having a tooth thereon pivotally mounted in the casing and positioned whereby the said tooth is adapted to drop into engagement with teeth of the said ratchet wheel, and means actuating the said latch bar for moving the tooth out of engagement with the teeth of the ratchet wheel upon closing of the sash.

2. In a window sash operator, the combination which comprises a window frame, a sash pivotally mounted in the window frame, a casing positioned on the window frame, an arm pivotally mounted in the casing and extended therefrom, means operatively connecting the extended end of the arm to the sash, said arm having a hub with worm gear teeth in the peripheral surface on the end thereof positioned in the casing, a worm gear positioned in the casing and meshing with the teeth of the hub of the arm, a shaft extended through the casing for mounting the worm gear, a tubu-

lar section slidably mounted on one end of the shaft, a hand crank carried by the outer end of the tubular section of the shaft, a ratchet wheel mounted on the tubular section of the shaft, a latch bar having a tooth thereon pivotally mounted in the casing and positioned whereby the said tooth is adapted to drop into engagement with teeth of the said ratchet wheel, means actuating the said latch bar for moving the tooth out of engagement with the teeth of the ratchet wheel upon closing of the sash, said tubular section of the shaft adapted to be moved inwardly for rotation thereof by the crank to operate the window sash, and resilient means within the shaft for moving the said tubular section and crank outwardly upon release of the crank.

3. In a window sash operator, the combination which comprises a box-like casing, an arm having a hub with worm gear teeth in the peripheral surface journaled through the hub in the casing, a worm positioned in the casing, a shaft journaled in the casing and on which the worm is positioned, said shaft positioned wherein the worm is in engagement with the worm gear teeth of the hub of the arm, a tubular section slidably mounted on one end of the shaft, a hand crank carried by the outer end of the said tubular section, a ratchet wheel mounted on the inner end of the tubular section of the shaft, a spring in the shaft for urging the said tubular section thereof outwardly, a latch bar pivotally mounted in the casing and positioned to ride upon the ratchet wheel with the ratchet wheel moved inwardly by the crank, said latch bar having a tooth on one side positioned to engage the teeth of the ratchet wheel with the ratchet wheel and crank moved outwardly by the spring, and a cam on the hub of the arm for elevating the latch bar for positioning the latch bar above the ratchet wheel.

4. In a window sash operator, the combination which comprises a window frame, a sash pivotally mounted in the window frame, a casing positioned on the window frame, an arm pivotally mounted in the casing and extended therefrom, means operatively connecting the extended end of the arm to the sash, said arm having a hub with gear teeth on the end thereof positioned in the casing, a gear positioned in the casing and meshing with the teeth of the hub of the arm, a shaft extended through the casing for mounting the gear, a tubular section slidably mounted on the shaft, a crank carried by the outer end of the tubular section of the shaft, a ratchet wheel mounted on the tubular section of the shaft, a latch bar having a tooth thereon pivotally mounted in the casing and positioned whereby the said tooth is adapted to drop into engagement with teeth of the said ratchet wheel, and means actuating the said latch bar for moving the tooth out of engagement with the teeth of the ratchet wheel upon closing of the sash.
